UNITED STATES PATENT OFFICE.

EDOUARD HENRI MARIE JOSEPH JUHELLÉ DE MARTILLY, OF PARIS, FRANCE.

EXTENSIBLE LAMP-SHADE FRAME.

Application filed May 26, 1921. Serial No. 472,788.

To all whom it may concern:

Be it known that I, EDOUARD HENRI MARIE JOSEPH JUHELLÉ DE MARTILLY, citizen of the Republic of France, and resident of Paris, France (post-office address, 26 avenue de Breteuil), have invented new and useful Extensible Lamp-Shade Frames, which improvements are fully set forth in the following specification.

10 The present invention relates to lamp fixtures and has for its object to provide a fixture which can be easily and readily positioned in a vase, pot or other receptacle used for ornamental purposes to transform 15 said receptacle into electric lighting devices.

With this and other objects in view my new device consists of an expandible frame made of two superposed sections, each composed of a plurality of curved and resilient wires or members, the members of the two sections being made to slidably interengage one another so that the frame can be expanded or contracted and can be mounted 25 within any vase, pot or receptacle so as to constitute with the latter a lamp, thereby eliminating the use of a special frame for each vase and reducing the cost of labor of such special frames. The device can be positioned in and removed from the receptacle 30 with the greatest ease and without spoiling the appearance of the receptacle and can be adjusted to any desired height according to the size of the lamp shade and of the receptacle or the desired lighting area for working and reading purposes.

With slight modifications and suitable ornamentation the device can be made to itself constitute a simple and practical electric 40 lamp.

One embodiment of my invention is shown in the accompanying drawing in which similar reference characters denote corresponding parts and in which Fig. 1 is 45 an elevation of my new lamp fixture shown extended to its maximum height; Fig. 2 is a similar view of the device entirely contracted and mounted in a vase; Fig. 3 is a similar view of the extended fixture embedded in a vase of different shape from that 50 shown in Fig. 2; Fig. 4 is an elevation of a modified form of construction, the fixture being shown provided with a base and serving itself as a lamp; Fig. 5 is a similar view 55 as Fig. 4, the fixture being equipped with means permitting the adjustment of the

lamp shade to different positions and Fig. 6 is a longitudinal section of the fixture showing the slidable connection between the two sections. 60

According to the construction of Figs. 1, 2 and 3, the fixture consists of a frame made of two superposed sections A, B, each composed of a plurality of curved and more or less resilient wires or members Y, Z. In the 65 present example each section is formed of four wires or the like, the members Z of the upper section radiating and extending upwardly from a hollow collar shaped base member h to which they may be soldered or otherwise fixed and the members Y of the lower section B radiating and extending upwardly from a disk shaped member b'. The upper ends of the members Z of the upper section have soldered or otherwise fixed to 70 them a pipe section b having a downwardly directed threaded extension c for engagement of the socket d of an electric bulb E. At its upper end the pipe section b is formed with a disk shaped extension t having a centrally threaded bore for engagement of a milled screw j whereby a lamp shade l 75 mounted on the disk t over the fixture, can be fixed in position. One of the members of the upper section may be looped as at f, f' 80 to form guides for the electric conductor wires or cords K leading from the socket d of the electric bulb. The members of the lower section are adapted to be passed thru the hollow of the base h of the upper section and to frictionally engage therein while their extreme free ends are bent to form loops r adapted to slidably engage the members of the upper section. When four 85 branch sections, as in the example shown in 90 Figs. 1-3 are used, the wires or members of the lower section are made to engage the wires or members of the upper section in a twisted manner, that is to say, the right wire or member Y of the lower section has its 100 loop r engage the left wire or member Z of the upper section, etc.

The device as described thus constitutes a frame capable of variable adjustment in its height. 105

In use the electric socket is applied to the tube c, the conductor wires or cords K are passed through the opening n of the tube and then the device is positioned within the vase v. The height of the frame is then adjusted according to convenience. The slidably interengaging wires or member Y, Z 110

are held in position by the frictional engagement of the members Y in the hollow of the base h . But in order to prevent accidental displacement, the parts may be tightened by 5 the set screw s . After passing the conductor wire or cord K through the loops f, f' the felt washer d' of the plate c' is coated with glue or paste and stuck onto the bottom of the vase v , as shown in Fig. 2, care being 10 taken to set it right in the centre and perfectly straight.

If it is preferred not to use glue or paste the vase, after the fixture has been positioned therein, is filled up to a suitable height with 15 saw dust, sand, earth, or the like m , which is pressed down so as to hold the device steady (Fig. 3). The lamp shade may then be fixed in position by means of the milled stud j .

20 When using glue or paste the device can be easily removed from the vase by pouring a little water into the latter to loosen the glue or paste.

For narrow necked vases such as v' in 25 Fig. 3 or such having uneven bottoms, the plate c' may be removed and the device planted in said vase by embedding it, as hereinbefore explained.

The device, can, of course, be made of 30 any size.

Instead of using the washer d' to be glued to the bottom of the vase, a pneumatic sucker, such as used for affixing candle sticks to mirrors, may be resorted to.

35 The device can also be formed with a base u , as shown in Fig. 4, so that it may itself constitute a lamp.

The fixture may be modified by reducing 40 its number of branches or members. Thus in Figs. 4 and 5 there are only two members composing each section, as at A', B' .

The fixture may be provided with suitable 45 means for the movable attachment of a lamp shade U' as indicated at w in Fig. 5, so that the shade can be adjusted to different positions to project the light in the desired direction.

What I claim and desire to secure by Letters Patent is:—

50 1. An extensible lamp fixture consisting of two superposed sections, each composed of a cluster of resilient members, the joint of the upper cluster being hollow and the members

of the lower cluster frictionally bearing in said hollow joint of the upper cluster and 55 slidably engaging the members of the latter and means for the attachment of an electric bulb to said fixture.

2. An extensible lamp fixture consisting of two superposed sections, each composed of a plurality of resilient members, a hollow member connecting the lower ends of the upper section together, means connecting the lower ends of the lower section together, the members of the lower section being adapted 60 to frictionally and slidably bear in said hollow member and slidably engaging with their extreme ends the members of the upper section and means for the attachment of 65 an electric bulb.

3. An extensible lamp fixture consisting of two superposed sections, each composed of a plurality of resilient members, a hollow member connecting the lower ends of the upper section together, means connecting the 70 lower ends of the lower section together, the members of said lower section being arranged in a twisted position and bearing frictionally and slidably in said hollow member and their extreme ends being adapted to 75 slidably engage the members of the upper section and means for the attachment of an electric bulb.

4. In an electric lamp, the combination 80 with a vase or the like, of a fixture consisting of two superposed sections, each composed of a plurality of resilient members, a hollow member connecting the lower ends of the upper section together, means connecting the lower ends of the lower section 85 together, the members of said lower section frictionally bearing in said hollow member and slidably engaging the members of the upper section, means for the attachment of an electric bulb to said fixture and means for 90 the attachment of said fixture to the bottom of the vase.

In testimony whereof I have signed this specification in the presence of two subscribing witnesses.

EDOUARD HENRI MARIE JOSEPH

JUHELLÉ de MARTILLY.
